CLAIM

The ornamental design for a surgical face shield, as shown and described.

DESCRIPTION

FIG. 1 is a top, front right-side perspective view of a surgical face shield;

FIG. 2 is a partial enlarged view of region 2 of FIG. 1;

FIG. 3 is a partial enlarged view of region 3 of FIG. 4;

FIG. 4 is a rear, bottom right-side perspective view thereof;

FIG. 5 is a front view thereof;

FIG. 6 is a rear view thereof;

FIG. 7 is a partial enlarged view of region 7 of FIG. 5;

FIG. 8 is a partial enlarged right-side view of region 7 of FIG. 5;

FIG. 9 is a partial cross-sectional view taken along axis 9 of FIG. 7;

FIG. 10 is a right-side view thereof;

FIG. 11 is a left-side view thereof;

FIG. 12 is a top view thereof;

FIG. 13 is a bottom view thereof; and,

FIG. 14 is a partial enlarged bottom view of region 7 of FIG. 5.

The evenly spaced broken lines depicting portions of the surgical face shield form no part of the claimed design. The dot-dash broken lines represent the bounds of the enlarged portions and form no part thereof.

1 Claim, 8 Drawing Sheets
